UNITED STATES PATENT OFFICE

THOMAS W. THORPE AND GEORGE E. THORPE, OF DES MOINES, IOWA

TOOL JACK

Application filed March 28, 1928. Serial No. 265,249.

The object of our invention is to provide a tool jack of simple, durable, and comparatively inexpensive construction.

A further object of our invention is to provide a tool jack for use with tools such as wrenches wherein the wrenches may be manipulated for tightening or loosening a joint such as the type used in well boring outfits where a threaded sleeve receives a threaded ¹⁰ stud.

Another object is to provide in a jack of this character a means for exerting a greater force for the final tightening of the joint without the use of additional operators to operate the jack when finally setting the joint.

Still a further object is to provide a jack of this character in which an arcuate track is adapted to receive a jack member which travels therealong by a step by step movement which movement is obtained by the actuation of a jack handle and an actuating pawl, with a means on one end of the track for obtaining additional power for moving the tools to tighten or loosen a joint.

Still a further object is to provide this last mentioned means in the form of a bracket secured to the track, a rod rotatably mounted relative to the bracket and a sleeve screwed on the rod, the sleeve being arranged to receive one of the tools. In this manner the jack member may be manipulated for tightening the joint as much as possible and the screw threaded rod and sleeve may then be manipulated for imparting additional movement to the tools for tightening the joint beyond a point possible by the use of the jack member alone.

With these and other objects in view, our invention consists in the construction, arrangement and combination of the various parts of our device, whereby the objects contemplated are attained, as hereinafter more fully set forth, pointed out in our claims and illustrated in the accompanying drawings.

Although the invention is susceptible of a variety of embodiments, it is unnecessary to fully describe and illustrate more than one in order to give a full understanding of the invention both from its structural and functional standpoints. Accordingly, we have illus-

trated a preferred and desirable embodiment of the invention in the accompanying drawings in which:

Figure 1 is a plan view of a jack embodying our invention and illustrated in use. ⁵⁵

Figure 2 is a front elevation of Figure 1 looking in the direction of the arrow 2.

Figure 3 is a side view partly in section illustrating a type of joint used in well boring, tools for which our jack is particularly ⁶⁰ adapted.

Figure 4 is a side elevation partly in section of the track the jack member and the tightening member of our device as taken on the line 4—4 of Figure 1. ⁶⁵

Figure 5 is a sectional view on the line 5—5 of Figure 4.

Figure 6 is a perspective view of the bracket member 46.

Figure 7 is a perspective view of the ⁷⁰ threaded rod.

Figure 8 is a perspective view of the threaded sleeve which coacts with the rod shown in Figure 7; and

Figure 9 is a sectional view through the ⁷⁵ head of the rod shown in Figure 7 illustrating the openings into which a bar may be thrust for turning the rod.

Figure 10 is a cross sectional view through the tool engaging member 70 with the bushing ⁸⁰ 74 therein.

On the accompanying drawings we have used the reference numeral 10 to indicate a rod such as used when boring wells. 12 indicates a tool which is secured to the rod 10. In well boring outfits, the rods 10 are of any suitable diameter and length and as many of them are used as is necessary to provide a given weight for the tool 12. The boring outfit consists of a means for moving the rods 10 and the tool 12 up and down so that the lower cutting edge of the tool may chisel into the ground and bore an opening into which a casing is inserted for the withdrawal of water or oil as the case may be. ⁸⁵ ⁹⁰ ⁹⁵

Each of the rods 10 is provided at its upper end with screw threaded studs similar to the screw threaded stud 14 formed on the upper end of the tool 12. Each stud 14 coacts with a threaded opening 16 formed in the ¹⁰⁰

bottom of the rod thereabove. The uppermost rod is secured to a cable running up to the well boring machine. It will be noted that the studs 14 and the openings 16 are tapered. This is so that when wear occurs between the threaded joints, the flat surfaces 18 which frictionally engage each other may be ground or turned down and the threads in this way kept tight even after the rods and the tools have been used considerably. The friction between the surfaces 18 is depended on for keeping the rod 10 in position relative to the tool 12 without unscrewing. It is therefore obvious that the joint must be tightened very tight in order to resist the continual pounding imparted on the joints by the up and down movement caused by the well boring machine.

In order to tighten the joint sufficiently for practical purposes a jack structure has been used which consists of an arcuate track 20 having a means at one end for engaging a wrench 22. The wrench 22 coacts with flat portions 24 formed on the tool 12 or rod 10 below a predetermined joint.

The top of the track 20 is serrated or provided with teeth 26 and a jack member 28 is slidably mounted on the track. The jack member 28 includes an operating lever 30 for moving a pawl 32 relative to the jack member. The pawl 32 coacts with the teeth 26 and when the handle 30 is oscillated the member 28 will advance along the track 20 in the direction of the arrow 36 due to this coaction and oscillation.

A holding pawl 34 is provided to prevent reverse movement of the jack member 28. The jack member 28 is provided with a hook portion 38 under which the end of a wrench 40 is hooked. The wrench 40 coacts with flat or square portions 42 of the rod 10 above the joint being tightened whereby movement of the jack member 28 along the track will rotate the rod 10 above the joint relative to the tool 12 or rod 10 below the joint being tightened. A brace 44 is usually provided to properly space the track 20 from the rod 10 and tool 12.

On one end of the track 20 we mount a tightening device A which embodies our invention in the present instance. The ordinary types of tool jacks have merely a hook member substituted for our device A so that the jack 28 is entirely depended upon for tightening the joint. By this old method the joint can be made fairly tight by an operator but the final setting up of the joint for giving the desired tightness to prevent loosening of the joint when in operation can only be had by the assistance of other operators in oscillating the handle 30 and even in this case the joint is not made as tight as desirable. It also requires the calling of other helpers or outsiders to assist in setting the joint to the desired tightness for operation.

The tightening device A consists of a bracket 46 having a pair of inwardly projecting lugs 48 adapted to coact with grooves 50 formed in the sides of the track 20. The bracket member 46 is held in position by a pin 52 extending into an opening 53 formed in one end of the track 20. The bracket 46 is provided with a cone shaped opening 54 the smaller end of which terminates in a concave seat 56.

A rod 58 extends through the opening 54 and is provided with a semi-ball shaped head 60. The convex side of the head 60 is adapted to coact with the concave seat 56 so that the rod 58 may be swung universally relative to the bracket 46 within certain limits. The head 60 terminates in a cylindrical portion 62 having a groove 64 formed in the end thereof. A pair of openings 66 extend through the portion 62. The rod 58 is screw threaded as indicated at 68. A tool engaging member 70 is provided consisting of a cylindrical or sleeve shaped portion internally screw threaded as indicated at 72. The threads 72 are adapted to coact with the threads 68 on the rod 58. The threads 72 are preferably formed in a bushing 74 which is pressed into or otherwise secured in the tool engaging member 70 as shown in Figure 10 although they may be formed directly in the member 70 as shown in Figure 8. A head 76 is formed on the member 70 and this head is provided with an opening 78. The opening 78 is adapted to receive the end of a tool such as the wrench 22 illustrated in Figures 1 and 2 of the drawings.

Practical operation

In the operation of our device the tools 22 and 40 are caused to coact with the portions 24 and 42 on each side of the joint to be tightened and the wrenches are manipulated to tighten the joint as much as possible by hand. The tool jack is then assembled in position as illustrated in Figures 1 and 2 and the jack member 28 is manipulated for tightening the joint as much as possible by the handle 30. Thereafter a bar 80 such as a crow bar may be inserted through one of the openings 66 in the head 60 and the rod 58 may in this manner be rotated for pulling the tool engaging member 70 toward the bracket 46. Since this is a screw threaded connection and considerable leverage may be exerted on the rod 58 by a single operator manipulating the bar 80 it is comparatively easy to set the joint very tightly.

Also for loosening the joint our device may be used by inserting the end of the wrench 40 through the opening 78 and hooking the end of the wrench 22 over the jack member 28. The bar 80 may first be manipulated for starting the loosening movement of the joint after which it is possible to further loosen the joint by the jack member 28.

Ordinarily the jack members 28 of tool jacks are provided with reversing mechanism but with my improved type of jack this mechanism may be dispensed with as the device A may be used for loosening the tools so that the pawls 32 and 34 may be lifted for moving the jack member in a direction opposite to the arrow 36 and thereby placing it in operation for another tightening or loosening job. It will be obvious that we have provided an efficient means which is easily operated for tightening a joint very tightly or loosening such a joint without the help of additional operators in manipulating the jack.

The groove 64 in the head 60 is adapted to receive the end of a wrench when it is not necessary to use the device A for tightening or loosening a joint.

Some changes may be made in the construction and arrangement of the parts of our device without departing from the real spirit and purpose of our invention, and it is our intention to cover by our claim, any modified forms of structure or use of mechanical equivalents, which may be reasonably included within their scope.

We claim as our invention:

In a tool manipulating device, an arc-shaped track, a tool jack and a bracket thereon, said tool jack having a tool engaging portion, said bracket having a tapered opening and a concave seat around said opening, a threaded rod through said opening, a convex shoulder thereon and engageable with said concave seat and an eye member having a tool receiving eye portion to receive an end of a tool and an internally threaded sleeve portion threaded on said rod.
